UNITED STATES PATENT OFFICE.

ARTHUR J. BLOOD, OF LYNN, MASSACHUSETTS.

RECEPTACLE FOR GRANULAR OR PULVERULENT MATERIAL.

No. 892,392.

Specification of Letters Patent.

Patented July 7, 1908.

Application filed May 20, 1907. Serial No. 374,564.

To all whom it may concern:

Be it known that I, ARTHUR J. BLOOD, a citizen of the United States, residing at Lynn, in the county of Essex and State of Massachusetts, have invented certain new and useful Improvements in Receptacles for Granular or Pulverulent Material; and I do hereby declare the following to be a full, clear, and exact description of the invention, such as will enable others skilled in the art to which it appertains to make and use the same.

The present invention relates to receptacles for containing and dispensing granular or pulverulent material and more particularly to an improved so-called "sifting top" for such receptacles.

The object of the present invention is to produce a simple and effective top or closure provided with a revolving plate and to so construct the plate that it may be readily turned for the purpose of opening and closing the receptacle without the liability of injury to the fingers of the operator.

To the above ends the present invention consists of the improved receptacle which will be hereinafter described and claimed.

The present invention is illustrated in the accompanying drawing, in which:—

Figure 1 shows a top plan view of my improved receptacle. Fig. 2 is a vertical sectional view of the same. Fig. 3 shows a top plan view of a modified form in which the revolving top is formed in substantially a half circle and having the turning bar along its straight edge. Fig. 4 is a vertical sectional view of the form shown in Fig. 3. Fig. 5 shows a further modification of the manner of providing the revolving top with a turning bar. Fig. 6 is a vertical sectional view of the form shown in Fig. 5.

Similar reference characters will be employed throughout the specification and drawing to designate corresponding parts.

In the drawing, 1 represents the receptacle, preferably cylindrical in form and made of tin or any other preferred material. The receptacle 1 is closed at the bottom and open at the top and the top opening is closed after the receptacle has been filled, by the top 2, which is preferably struck up from sheet metal, and is provided with a vertical wall 3, which may be secured in any suitable manner, as by turning over the edge 4 and soldering it to the upper edge of the receptacle.

As so far described, the three forms illustrated are exactly alike, and in each form the

top 2 is depressed below the upper edge of the receptacle, leaving a chamber 5. In the form shown in Fig. 1, the top 2 is provided with openings 6, 7 and 8, the opening 6 being preferably a circular opening, the opening 7 being segmental slots, and the opening 8 small perforations arranged in segmental form. In this form of the invention, the receptacle is provided with a revolving disk or plate 9, substantially circular in general outlines and provided with a segmental opening 10 formed by cutting out the metal in such a way as to leave a bearing 11 at the center which receives a rivet 12 which passes through the top 2, and preferably through a spring washer 13 upon the under side.

To facilitate the ready turning of the revolving disk or plate 9, the radial edges of the segmental opening 10 are turned upwardly at right angles to the surface, forming the vertically extending turning bars 14, which extend upward a sufficient distance to be grasped by the fingers of the operator, but preferably within the top or marginal edge of the receptacle.

From the foregoing construction it will be observed that when the revolving plate 9 is in the position shown in Fig. 1, all of the openings, 6, 7 and 8 will be closed, and that by grasping the upturned bars 14, the revolving disk 9 may be turned to bring the opening 10 in register with any one of the openings, 6, 7, or 8, as may be desired.

In Figs. 3 and 4 the revolving plate 15 is formed a little larger than half the diameter of the top, and it is pivoted to the top 2 by the rivet 16, which passes through the top and through the spring washer 17. In this form of the device the top 2 is provided with a group of perforations 18, located entirely to one side of a line intersecting the diameter, the other side of the top being imperforate. The straight edge of the plate 16 will be turned upwardly forming the turning bar 19, which will extend substantially across the top of the receptacle and to one side of a line intersecting its diameter, and like the form shown in Fig. 1, the turning bar will be within the upper edge of the receptacle. In this form of the device the bar 19 may be grasped and the plate 15 turned about its pivot 16 to cover or uncover the perforations 18.

In the form shown in Figs. 5 and 6, the revolving disk or plate 20 is pivoted by the central rivet 21, which also passes through a spring washer 22. The revolving plate 20 is

provided with a circular opening 23 and the top 2 is provided preferably with a group of openings 24, 25 and 26, the opening 24 being a circular opening, the opening 25 being a group of slots, and the opening 26 a group of perforations. In this form, the disk 20 is provided with a bail 27 fastened at its ends in any convenient manner, to the disk 20. The preferred manner of attaching this bail 10 is shown, and consists in striking up from the disk 20 the bars 28 and passing the ends 29 of the bail 27 beneath these bars 28, which are then forced or swaged by pressure upon the ends 29 to clamp the ends 29 and thus firmly 15 secure the bail 27 in position.

Having described my invention I claim as new and desire to protect by Letters Patent of the United States:—

1. A can or receptacle for granular or pul-
20 verulent material having a depressed fixed

top with suitable openings therein, a centrally pivoted plate mounted upon the top cut away to form an opening and having an edge adjacent the opening turned up to form a turning bar, substantially as described. 25

2. A can or receptacle for granular or pul-
verulent material, having a depressed fixed top, openings in said top at one side of the diameter thereof, a plate pivotally mounted upon the fixed top and having its edge turned 30 up forming a turning bar adjacent to, and parallel with the diameter, substantially as described.

In testimony whereof I affix my signature, in presence of two witnesses.

ARTHUR J. BLOOD.
